AIR PUMP

Leonard Alfred Popp, Saugus, Mass., assignor to
Lawrence E. Johnson, Melrose, Mass.

Application December 4, 1935, Serial No. 52,861

12 Claims. (Cl. 221—73.5)

This invention relates to an improvement in air pumps, more particularly to that class of devices which are designed to discharge a quantity of air under pressure into a plumbing fixture whereby to remove the stoppage therein without the necessity of dismantling the fixture.

One object of my invention is to provide new and improved devices of the above character adapted for clearing obstructions or stoppages in drains, toilets, wastepipes and the like which will operate with greater facility, than has obtained in devices of this character as heretofore constructed.

Another object of the invention is to provide a device of this character wherein the pumping device is mounted and carried upon a removable head of an air pressure reservoir whereby access to the pump and associate mechanism may be more readily had than has attained in devices of this character as hitherto constructed.

Another object of the invention is to provide new and improved means for releasing the compressed air in a device of this character.

Another object of the invention is to provide a device of the above type which is compact in form, simple in construction, easy to operate and which may be employed for the purposes indicated with great efficiency.

A further object of the invention is to provide a device of this character which may be readily disassembled for cleaning, lubrication or replacement of parts.

Other objects and aims of the invention, more or less specific than those referred to above, will be in part obvious and in part pointed out in the course of the following description of the elements, combinations, arrangements of parts and application of principles, constituting the invention; and the scope of protection contemplated will be indicated in the appended claims.

In the accompanying drawing wherein I have illustrated preferred embodiments of my invention,

Figure 1 is a vertical sectional view taken through my improved device, certain of the parts being shown in side elevation, the view being taken substantially on line 1—1 of Figure 2.

Figure 2 is a top plan view with certain of the parts omitted in the interest of clear illustration.

Figure 3 is a broken vertical sectional view of the device taken substantially on line 3—3 of Figure 2.

Figure 4 is a horizontal sectional view taken on

the line 4—4 of Figure 3, the pressure cap mounted upon the lower end of the device being omitted.

Figure 5 is a vertical sectional view taken through the lower end of the device, certain of the parts being shown in vertical elevation, illustrating the means for releasing the compressed air in the reservoir, and

Figure 6 is an enlarged sectional elevation illustrating the check valve mechanism.

Referring now to the drawing wherein similar reference characters refer to similar parts throughout the several views thereof, the reference numeral 10 denotes an elongated circular casing which forms a reservoir for the compressed air and 11 denotes a removable head for the reservoir, said head being secured in position by means of stay or tie rods 12. These tie rods, as shown in Figure 3, are screw threaded into the head, extending vertically through the pressure reservoir and through a head 14 mounted upon the lower end of the cylinder 10, nuts 13 being mounted upon the rods 12 whereby both of the heads 11 and 14 are securely clamped upon the upper and lower ends of the cylinder 10. If desired, suitable gaskets may be employed between the heads and the ends of the cylinder to insure an air-tight chamber within the cylinder 10.

The reference numeral 15 denotes an air outlet pipe which is extended into the reservoir, the upper ends of which is provided with a valve seat 16, adapted to receive a valve 17 which is normally seated on the seat 16 to effect a closure of the outlet pipe 15.

This outlet pipe is secured to the bottom head 14 by any suitable means, in the present instance it is shown as being pressed in.

The outlet pipe is threaded exteriorly at its lower end so as to receive a screw threaded sleeve of a cap 18 preferably formed of rubber, the sleeve of said cap being adapted to be held in an adjusted position as by means of the lock-nuts 19 and 20.

The purpose of the cap 18 is to effect a seal in the opening of the conduit to be cleared of obstructions. If desired, the cap 18 may be reversed for insertion into the conduit when it is more convenient to be employed in this manner.

The air pump shown herein comprises a barrel 21, rigidly secured to the head 11 in any desired manner and located in the barrel 21 is a piston or plunger 22 mounted upon a piston, or a plunger rod 23 which extends upwardly through the head 11, the upper end of which is provided with the operating handle 24.

The reference numeral 25 denotes a check-valve preferably of the type known as the "Schafer" valve commonly employed in connection with pneumatic tires. This valve permits 5 air compressed by the action of the pump to be forced into the reservoir at each downward stroke of the pump plunger, but automatically closes to prevent escape of the air from the reservoir.

Referring now to Figure 6 wherein this check-10 valve is shown, said valve includes the tube 50 threaded to engage the lower end of the pump barrel, a nut 51 securing the tube firmly in position.

The exterior of the tube 50 is counter-bored 15 and tapped to receive the threaded member 52, having an extension 53 tapered to provide an air-tight connection with a corresponding taper provided in the tube.

Through the threaded member 52 extends a 20 loosely fitted stem 54 to which is rigidly mounted the valve 55 normally resting on the end of the extension 53, the spring 56 resting on a collar 57 abutting the shoulder 58 in the tube.

The stem 54 is axially movable in the collar, 25 and the spring yieldingly pressing the valve 55 of its seat.

Compressed air from the pump depresses the valve and the air is forced through the orifice 60 into the reservoir formed by the casing 10, the 30 valve reseating as the pump plunger moves upwardly. The end of the tube 50 is threaded exteriorly to permit the nut 59 to secure the tube firmly in the stirrup 33.

The outlet pipe 15 is preferably axially aligned 35 with the reservoir and the pump barrel is preferably axially located with respect to the outlet pipe 15. The valve 17, in any event, seats axially with the outlet pipe 15 and is mounted and operated in the following manner:

40 Slidably mounted upon the pump barrel 21 is a sleeve 26 and rigidly associated with the sleeve 26 is the stirrup 21, the valve 17 being mounted upon a cross member formed upon the lower end of the stirrup.

45 The valve 17 is loosely mounted on the stirrup so as to permit automatic adjustment to the seat 16 as by means of the screw 28 which passes through the valve, the nut 29 and the washer 30 securing the valve thereto. The screw 28 passing

50 through the cross-member 31 of the stirrup 21 bottoms in the nut 32, thereby permitting a slight play of the valve 17 with respect to the seat 16.

Extending from the end of the pump barrel 21 55 is a second stirrup 33 hereinbefore mentioned, through which the check-valve extends as has already been described.

The U shaped lever 34 passes between the end 60 of the sleeve 26 and inside of the bottom member of the stirrup 33. Abutting the stirrup 33 and reacting on the stirrup 37 in which the valve 17 is mounted is the helical spring 35 which operates normally to seat the valve 17 on the end 65 of the outlet pipe 15 and engage the sleeve 26 and the stirrup 33 with opposite edges of the U shaped lever 34. The free arms of this lever are extended and the stem 36 is swivelled thereto at 37 by means of the cotter pin 38.

The stem 36 extends through the head 11, the 70 gland 39 and packing 40 providing against air leakage from the reservoir.

The button 41 on the end of the stem 36 facilitates the raising of the valve 17 from its seat to release compressed air from the reservoir.

75 Referring to Figure 5, it will be seen that the

valve 17 may be raised from its seat either by pulling action on the button 41 as indicated at A, or by pressing the button downwardly as indicated in the dotted lines B. In either case the U shaped lever 34 fulcrums on the crossbar of the 5 stirrup 33 to lift the sleeve 26.

By means of the construction shown and described, the valve 17 is quickly raised from its seat so that the accumulated air in the cylinder is instantly released and discharged through the seal 10 provided by the cap 18 in the conduit containing the obstruction which is to be removed.

The orifice 42 in the head 11 admits air into the pump barrel as the plunger thereof is forced downwardly and a pressure indicator 43 is mounted upon the head 11 and is in communication with the air of the reservoir within the cylinder 10 through the conduit 44.

In using my improved device, it is desirable to insert the cup 18 either in the position shown in 20 the drawing or in a reversed position as hereinbefore described, in the mouth of the conduit containing the obstruction. It is desirable that the space within the conduit below the cup be filled with water which is, of course, usually the 25 case unless the obstruction permits a slow seepage of water through the conduit. If this seepage occurs, the conduit should be refilled with water below the cup and the cup itself should be emersed in water above the edge which forms the seal in 30 the conduit from which the obstruction is to be removed.

Inasmuch as water is not compressible, the sudden release of the compressed air in the reservoir acts as a water hammer or ram to permit a 35 sudden blow to the obstruction, the force of said blow being determined by the amount of air pressure accumulated within the reservoir. Thus the stoppage is removed instantly and completely 40 without damage to the trap, pipes or other fittings.

The sudden release of the air pressure as above 45 described is affected by merely compressing or raising the rod 26 through the instrumentality of the button 41.

It will accordingly be seen that I have provided a construction well adapted to attain, among others, all the ends and objects above set forth in a most facile manner.

As many changes could be made in this construction without departing from the scope of the following claims, it is intended that all matter contained in the above description or shown in the accompanying drawing shall be interpreted 55 as illustrative only and not in a limiting sense.

Having thus described my invention what I claim as new and desire to secure by Letters Patent is:

1. In an air pump having an enclosing reservoir 60 provided with an outlet, and operative from the exterior of the reservoir, and including a barrel and a check valve operative to admit compressed air to the reservoir, in combination therewith, a member slidable on the pump barrel; a valve secured thereto and adapted to close the outlet from the reservoir; a projection from the pump barrel; a spring abutting the projection and reacting on the valve to close the outlet from the reservoir; and means operative from the exterior 65 of the reservoir to move the slidable member on the pump barrel to uncover the outlet from the reservoir.

2. In an air pump of the character described in claim 1, the operating means being adapted to 75

move the slidable member axially on the pump barrel.

3. In a pump of the character described in claim 1, the means for moving the sliding member including a lever engaging the slidable member and the abutment on opposite edges, and adapted to swing on the abutment.

4. In a pump of the character described in claim 1, the means for moving the slidable member including a lever engaging the slidable member and the abutment on opposite edges, and adapted to swing on the abutment; a stem connected to the lever, projecting through the head of the reservoir and movable axially thereof.

15 5. An air pump having an enclosing reservoir provided with an outlet and a removable head, the pump being mounted on the removable head and including a pump barrel and a check valve operative to admit compressed air to the reservoir; a sleeve slidable on the barrel; a valve secured thereto and adapted to close the outlet from the reservoir; a stirrup depending from the pump barrel; a lever extending through the stirrup and engaging the stirrup and the sleeve on opposite edges; a spring abutting the stirrup and reacting on the valve to seat it over the outlet from the reservoir; a stem connected to the lever and extending through the head of the reservoir, and adapted to swing the lever within the stirrup 20 and move the sleeve axially on the barrel and uncover the outlet from the reservoir by any axial movement of the stem.

6. An air pump of the character described in claim 5, in which the outlet from the reservoir is axially aligned with the pump barrel.

35 7. A pump of the character described in claim 5, in which the sleeve, the lever and the valve may be removed by disconnecting the operating stem for the lever.

40 8. A pump of the character described in claim 5, in which the securing means for the closure valve permit automatic adjustment of the valve to its seat.

45 9. A pump of the character described in claim 5, in which the securing means for the closure valve include a stem rigid with the valve and movably secured in a dependent member integral with the sleeve, permitting automatic adjustment of the valve to its seat.

50 10. A device of the class described for removing obstructions in plumbing fixtures comprising a circular casing forming an air pressure reservoir, a head clamped to the upper end of said casing, a pump barrel centrally located with respect to said casing and carried by said head, a plunger transversing said pump barrel, an operating rod attached to said plunger and extending outwardly through said head, a check valve in said pump barrel for admitting air to said pressure chamber, a head secured to the lower end of said casing, an air exit pipe extending through said last named head, the upper end of said pipe having a valve seat, a valve slidably supported upon said pump barrel co-60 operating with said valve seat and spring pressed

thereagainst, a rod associated with said spring for opening and closing said last named valve, said rod extending upwardly through said pressure chamber and through the head clamped to the upper end of said casing, and said last named 5 valve, said check valve and said pump barrel having their central axes located in the same plane.

11. A device of the class described for removing obstructions from plumbing fixtures by the use of compressed air comprising a circular casing forming an air pressure reservoir, heads clamped respectively to the upper and lower ends of said casing so as to form an air-tight enclosure, a pump barrel supported by said uppermost head and extending downwardly through said casing and centrally located with respect thereto, a plunger located in said casing, having an operating rod extending upwardly through said uppermost head and having an operating 15 handle at its upper end, a check valve located beneath said plunger for admitting air into said reservoir, a pipe extending through said lowermost head having a valve seat, a valve co-operating with said valve seat, a sleeve slidably 20 mounted upon said pump barrel, a spring interposed between said sleeve and said last mentioned valve, a lever associated with said sleeve to raise and lower the same whereby to open and close said last named valve and an operating 25 rod connected with said lever and extending upwardly through the head mounted upon the upper end of said casing.

12. A device of the class described for removing obstructions by air pressure from plumbing fixtures, comprising a cylindrical casing having heads clamped to each end thereof to form an air pressure reservoir, a pump barrel supported from the uppermost of said heads, a plunger in said pump barrel, an operating rod extending 35 downwardly through said uppermost head and connected with said plunger, a check valve located beneath said plunger for admitting air from the pump barrel to said reservoir, a pipe extending through said lowermost head provided with a valve seat at its upper end, a valve co-operating with said valve seat whereby to open and close said communication with said air pressure reservoir and said pipe, a sleeve slidably 40 mounted upon said pump barrel, a coil spring 45 extending between said last named valve and supported by said sleeve, a lever connected with said sleeve, an operating rod connected with said lever and extending upwardly through the uppermost of said heads, the connection between 50 said lever and said sleeve being such that either a downward movement of said operating rod or an upward movement thereof will cause said lever to raise said sleeve whereby to open said last named valve, a rubber cup mounted upon 55 the lower end of said air exit pipe and said exit pipe, said valves and said pump barrel having the lower end of said air exit pipe and said exit pipe, said valves and said pump barrel having their several axes in direct alignment.
